UNITED STATES PATENT OFFICE

AUGUST H. LEIPERT, OF COLLEGE POINT, NEW YORK, N. Y., ASSIGNOR, BY MESNE ASSIGNMENTS, TO THE RUBBER SHOCK INSULATOR CORPORATION, OF WILMINGTON, DELAWARE, A CORPORATION OF DELAWARE

NONMETALLIC PAVING BLOCK AND METHOD OF MANUFACTURING THE SAME

Application filed November 16, 1926. Serial No. 148,629.

In co-pending United States applications Ser. No. 722,648 filed June 27, 1924, now Patent No. 1,640,460 and Ser. No. 726,441 filed July 17, 1924, now Patent No. 1,643,024, 5 issued jointly to A. F. Masury and A. H. Leipert, there are shown, described and claimed non-metallic paving blocks of which a roadway may be comprised and methods of laying the blocks. It is there proposed 10 to retain the yielding non-metallic material, such as rubber, of which the blocks are composed under compression, whereby their strength, resiliency and wearing qualities are materially improved. These blocks when 15 placed under compression and laid to form the surface of a roadway afford a degree of non-rigidity, whereby shocks may be cushioned and noise deadened during the passage of vehicles thereover. Roadways having 20 a surface made up of blocks of such material have been found to show practically no perceptible wear in even the most trying conditions of usage over long periods of time.

The present invention is concerned primarily with a non-metallic paving block somewhat similar in general to the block shown and described in the second above-named application and method of manufacturing the same. The improved block differs 30 principally in the means for retaining material of which the block is composed under compression. In accordance with the invention the block comprises a preferably seamless metallic ring or band which encircles a 35 block of yielding non-metallic material substantially about its middle portion thereby maintaining it under compression, the ends being free and bulging slightly so that when laid to form a roadway the surface thereof 40 will be wholly non-metallic.

The improved method consists essentially in introducing a mass of yielding non-metallic material into a seamless metallic band under the application of external forces, 45 whereby the non-metallic material confined within the band is maintained under a degree of internal static pressure depending upon the relative dimensions of the mass of non-metallic material and the band.

50 In practicing the method the band is placed

upon a fixture which supports it upon two ledges in such a manner that the bottom may be left open and the rubber block forced therethrough. Over the top of the band is placed a funnel-shaped fixture designed for 55 the purpose of initially contracting the block. The block of non-metallic material, the outside dimensions of which are greater than the inner dimensions of the band is placed within the funnel-shaped fixture and forced 60 through the ring by any convenient means, such as a power press. The funnel-shaped fixture serves the purpose of initially contracting the block to the inner dimensions of the band thereby facilitating its passage 65 therethrough. When the funnel-shaped fixture is removed the band remains about the middle portion of the block thereby maintaining it under compression.

In order that the invention may be better 70 understood, it will now be described more fully in connection with the appended drawings in which:

Figure 1 is a view in perspective of a block 75 of non-metallic material, suitable for use as a paving block before being placed under compression.

Figure 2 is a view in perspective of a band 80 adapted to be placed about the middle portion of the block to maintain it under compression.

Figure 3 is a view in perspective showing 85 the band in place on a fixture adapted to hold it against displacement while the block is being forced therethrough.

Figure 4 is a view in perspective of the 90 funnel which is adapted to be placed above the band to facilitate forcing the block therethrough.

Figure 5 is a view showing the band and 95 funnel in place upon the fixture with a block of non-metallic material being forced therethrough by means of a power press, part of the funnel being broken away in the interest of clearness.

Figure 6 is a view in perspective of the 100 block with the band in place thereon and maintaining it under compression.

Figure 7 is a view in vertical section of the fixture, band and funnel with a block of non-

metallic material being forced therethrough, and showing an alternate form which the funnel may take in order to maintain the band in proper relation with the bottom of the funnel during the process.

5 There is disclosed in Figure 1 a block *a* of yielding non-metallic material, the edges of which may be beveled as at *a*¹, which it is proposed to confine under compression with 10 in a preferably seamless ring or band *b* designed to be placed about the middle portion of the block as shown in Figure 6. The inner dimensions of the band *b*, as from *b*¹ to *b*² and *b*³ to *b*⁴, are less than the outer dimensions of the block, as *a*¹ to *a*² and *a*³ to *a*⁴, so that when the band is placed about the block the yielding non-metallic material will be placed under a degree of compression and 15 internal static pressure depending upon the relative dimensions of the band and the block.

10 An apparatus adapted to force the yielding non-metallic material into the band is shown in Figure 5. The band *b* rests upon shoulders *d*⁴ carried with the fixture *d* and over 15 the band is placed a funnel-shaped fixture *c*. The fixture *d* may be formed, as shown in Figure 3, of two angle pieces having horizontal and vertical sides *d*¹, *d*², respectively, and held together in fixed relation by a piece of 20 metal *d*³ welded or otherwise affixed thereto. Upon the adjacent vertical sides *d*² are affixed shoulders *d*⁴ having formed thereon ledges *d*⁵ adapted to hold the band. On the outer edges of the vertical sides *d*² there may be formed 25 ears or brackets *d*⁶ having bolt holes formed therein for a purpose which will become apparent hereinafter.

20 The funnel-shaped fixture (Figure 4) may be formed of a single piece of metal having opposite sides converging as indicated at *c*¹, *c*² from the largest portion at the top *c*³ to the smallest portion *c*⁴ at the bottom. The small bottom portion *c*⁴ may be formed of sides whose elements are mutually perpendicular from *c*¹ to the bottom edge of the funnel *c*² and is so dimensioned that the inner bottom edges of the funnel coincide with the inner side of the band *b* when the funnel-shaped fixture *c* is placed thereupon. The 25 funnel-shaped fixture may have formed thereon ears or brackets *c*⁵ having bolt holes *c*⁶.

25 In forcing the non-metallic block into the band the band is placed upon the ledges *d*⁵ on the shoulders *d*⁴ carried with the fixture *d*. The funnel is then placed over the band in such relative position that the inner bottom edges of the funnel coincide with the inner edges of the band. As shown in Figure 5 30 the block of non-metallic material is then placed within the funnel and over it is arranged a ram *f* of wood or other suitable material which is adapted to force the block downwardly and through the band by means 35 of a power press indicated in part at *e* and

adapted to be operated by rollers as shown at *e*'. It will be observed that in being forced into the band the block of non-metallic material is contracted to the inner dimensions of the band while within the funnel as at *a*⁷ thereby facilitating its passage through the band.

40 Figure 7 is a view in vertical section showing a slight modification in the construction of the bottom portion of the funnel. It will be seen that the bottom portion may be machined out as indicated at *c*⁹ so as to fit about the band and assist in maintaining the proper relative position between the funnel and the band while the non-metallic material is being 45 forced therethrough. The proper relationship of parts may be also insured by clamping together the brackets *c*⁸ on the funnel and brackets *d*⁶ on the fixture as by bolts *h* passing through the bolt holes *c*⁶ and *d*⁷, respectively.

45 The completed paving block is shown in Figure 6 with the band in place about its middle portion. The ends of the non-metallic material may project beyond the edges of the band and bulge out as indicated at *a*⁸ the material confined by the band being under a greater degree of compression than that projecting beyond.

50 In practicing the improved method herein proposed the mass of yielding non-metallic material is forced into a seamless non-metallic band by the application of external forces. The method will be best understood with reference to the use of the apparatus illustrated in Figure 5. The yielding non-metallic material is forced into a band *b* held in place upon a fixture *d* under the action of the ram *f*, the funnel-shaped fixture being adapted to initially contract the mass of yielding non-metallic material to the inner dimensions of the band. It will be apparent, 55 however, that the means for introducing the mass of yielding non-metallic material into the band may take other forms than that shown in the preferred embodiment and no 60 limitations are intended except as indicated in the appended claims. It will also be obvious that the band *b* may be formed with circumferential corrugations or other means to reinforce it against the pressure set up by 65 the compression of the yielding non-metallic material.

70 It will thus be seen that there has been provided a paving block of yielding non-metallic material which is maintained under compression by a seamless metallic band and which presents a neat appearance having no 75 projections or other incumbrances which might cause difficulty in laying the blocks side by side in paving a roadway. The process of manufacture is simple and inexpensive and affords means of producing such paving blocks in quantities not heretofore possible. It will be seen that the paving block presents 80 a wholly non-metallic surface to the road.

way thereby cushioning shocks and deadening noises due to the passage of vehicles thereover. Since it is maintained under compression its resiliency and wearing qualities are such as will allow its continued use without replacement over a practically indefinite length of time.

5 What is claimed is:

In the manufacture of paving blocks, the
10 method of inserting a block of yielding material into and against a relatively rigid metallic retaining band which is somewhat smaller than the normal perimeter of the block, comprising firmly supporting the band,
15 compressing at least a part of the block in suitable means aligned with the band until one end of the block has a perimeter equal to the interior perimeter of the band, positioning the means and block so that the block
20 is aligned with the band, the compressed end of the block being next to the band, and forcing the block from said means directly into the band until it protrudes from both ends thereof, the block having no chance to expand
25 before coming within the band, and the said means remaining always entirely without the band though abutting against it.

This specification signed this 13th day of November A. D. 1926.

20 AUGUST H. LEIPERT.
